UNITED STATES PATENT OFFICE

AUGUST KAUFMANN, OF TAMPA, FLORIDA

CARD TABLE

Application filed November 23, 1928. Serial No. 321,462.

My invention relates to card tables of the conventional type, and more particularly to devices incorporated in such tables for the assistance of the players, and my main object is to provide a novel table-top structure with an array of signal devices which may be handily operated to indicate incidents in the card game.

A further object of the invention is to incorporate a set of signal devices peculiar to the incident of dealing cards, such devices operating to indicate the particular station next due for dealing the cards.

A still further object of the invention is to provide an array of signals whereby to indicate the chosen trump during a given deal.

Another object of the invention is to design the signal elements so as to be read directly upon the surface of the table, yet have the latter flush and without any impediments or obstructions.

A significant object of the invention is to provide a system of controls for the signal arrangement at the site of each station, to enable each player to fully operate the signal arrangement.

A final, but nevertheless important object of the invention is to construct the novel table-top along simple lines and with an operative mechanism of a character familiar to those skilled in the particular art.

With the above objects in view and any others that may suggest themselves in the specification and claims to follow, a better understanding of the invention may be had by reference to the accompanying drawing, in which—

Figure 1 is a plan view of the novel table-top;

Fig. 2 is an edge view thereof, partly broken away; and

Fig. 3 is a diagrammatic view illustrative of the electrical circuits employed for the invention.

It is a familiar fact that in the playing of the more popular card games the difficulty often presents itself as to who is the next dealer, the players having become so absorbed in the movements of the current deal

that the station or identity of the party next to deal escapes their minds, and the game is necessarily interrupted by an argument to settle the point. The same condition applies to the maintenance of a given trump, it frequently being a matter of doubt between the players as to what trump was declared. The two items in question thus require the attention and memory of the player along lines actually extrinsic of the workings of the game, and it is my intention to relieve the players of the responsibility to memorize or keep track of these items in order to avoid confusion, mistakes, or the possibility of one or more players taking advantage in this respect through lack of vigilance on the part of another player or players. I have therefore devised the novel signal arrangement to relieve the players of special attention along these lines and to make the operation of the dealing and trump incidents positive and visible to all the players.

Referring specifically to the drawing, 5 denotes the table-top and 6 the legs of a conventional card table suitable for four players. The table top is flat, and for the purpose of the signals referred to above, I build the table-top hollow and cut the top surface thereof with a series of openings corresponding to the positions of the legends 70 indicating the signals. The openings are flushly inlaid with glass panels 7, and under each panel I provide an electric lamp unit 8 whereby to illuminate the panel.

The arrangement of the signal panels is 85 in a cluster about the center of the table. Thus, I first provide legends in the form of outwardly pointing arrows, these being marked A', B', C', and D'. The arrow legends are arranged like the points of the compass, the arrows pointing to the stations of the players. Between the arrow legends I provide legends E', F', G', and H' for the typical card suit. Thus, the legend E' is that of clubs, the legend F' of hearts, etc. In 90 the center, I provide no legend indicator but the dial T' of an ordinary clock.

The arrows and the suit legends are painted, etched or otherwise marked on the under side of the panel facing; however, the panel 100

for the clock indicator is left plain for the clear vision of the clock dial below.

In order to signal the incidents of the arrangement just described, I provide an electric network within the table-top, controlling the same by a set of push buttons marked A, B, C, etc. to correspond with the marking of the indicator legends. Each side of the table is equipped with a like set of push buttons, the only difference in the marking of the push buttons being that the first or central push button has the marking of the arrow legend at a point 90° distant in a clockwise direction, that is, on the left hand side of the player opposite the push button mentioned. Thus, the push button A is opposite the arrow D', the push button B is opposite the arrow A', etc. However, the controlling factor of the push buttons is true to the corresponding legends, so that the operation of the push button A illuminates the lamp under the arrow A', the operation of the push button B illuminates the arrow B', and so on. Also, the operation by any player of the buttons E, F, G, or H, serves to illuminate the particular suit legend E', F', G', or H'.

The electrical circuit involved in the control of the signal indicators is so arranged that the operation of any arrow button A, B, etc., imparts continuous energy to the corresponding lamp; also, such operation serves to extinguish any of the suit indicators E', F', G', or H' that may then be in operation. The circuit is further designed that when once a given arrow indicator receives illumination, any push button E, F, G, or H may be operated to light the lamp of a corresponding suit indicator E', F', G', or H', so that both the chosen arrow indicator and the chosen suit indicator remain lighted. The design of the circuit further permits of an independent clock control T opposite each player. This control is, however, of a momentary character, so that when any push button T is operated, the dial of the clock becomes illuminated, yet promptly darkened as soon as the player removes his finger from the corresponding push button.

The indicator legends are ordinarily dark and almost invisible, for which reason I have illustrated them with a dotted and hazy effect, except for the legends E' and D', which are solid to indicate that they are in operation.

To operate the novel signal arrangement, it may be assumed that a player is seated at each side of the table and is ready to operate any of the set of push buttons handily located in front of him. It is noted that the push buttons are projected from the edge of the table with an upward slant, whereby to expose the markings thereof for easy inspection by the player. It is thus a handy matter to operate any push button without changing the position of the player; also, the push

buttons being in the edges of the table, are out of the way, leaving the entire table top clear for the playing of the game.

Assuming that a given player, such as the one opposite the arrow C', is dealing, it is necessary for the operation of the signal arrangement that he operate the push button D immediately in front of him when he has completed the deal. As heretofore explained, the arrow indicator D', to the left of the player, will then become illuminated indicating during the entire play of the particular deal that the player on the left is next to deal. At the same time, with a given trump declared, such as E, it is preferably the rule that the player receiving the bid operate his push button E to illuminate the corresponding trump indicator, as shown in the drawing. Thus, during the entire play, it is evident to all the players that the suit of clubs is the trump. On the next deal, the player opposite the push button A finally operates the same as did the previous dealer, for the purpose of putting into action the next deal indicator, which is the arrow A'. However, the act of operating the push button A immediately extinguishes the lamp of the trump indicator E', so that this trump has ceased to exist and the game is open for the selection of a new trump. Needless to say, in a game without trumps, the trump push buttons receive no attention and the circuit in no way interferes with the operation of the dealer indicating signals.

It is thus seen that the novel arrangement makes for positive and unmistakable indications of the factors auxiliary to the playing of the game. It is a simple matter for the player to become accustomed to the operation of the respective sets of push buttons and before long the controls may be operated as a matter of course and without any particular attention or deviation from the workings of the game. In other words, the operation of my signal arrangement will become a more or less mechanical incident, quite the same as the handling of chips, the shuffling of cards, or any other movement which requires no particular attention or concentration on the part of the players. They may therefore concentrate their minds fully upon the workings of the game and save considerable time and argument through the fact that they are relieved of attention and responsibility relative to the auxiliary or secondary features of the game. Also, the nature of ascertaining the time is easily at the convenience of any one of the players, the operation of the proper push button immediately illuminating the clock dial for the brief period necessary to observe the same.

I have illustrated in Figure 3 a typical electrical wiring system for the operation of my signal arrangement. For this system the push buttons E, F, etc. are of metal, passing

through a metallic panel 5 in each side of the table and being held out by springs 10. The inner end of each push button—except the buttons T—is made with an insulation marginal flange 11. Basically, I provide three wiring mains 12, 13 and 14, and have illustrated the application of these to so much of the wiring as is controlled by one player, only duplication in connection with these mains being required for each additional player.

The main 12 is simply a current supply for one terminal of all the lamps 8; the main 13 relates to a light restoring relay; and the main 14 is a common connection for any except the T buttons.

Taking any button except T, such as E, the advance thereof connects its inner end with a flexible blade 15 held by a bracket 16 of the main 14. With the current source at 17, a circuit is now established as follows: Button E, blade 15, bracket 16, main 14, relay magnet 18, conductor 19, source 17, conductor 17^a, main 12 and panel 5^a. The result is the attraction of relay armature 18^a to break contact 13^a with the main 13. This move extinguishes any lamp 8 (except for indicator T') that may have been in operation by breaking at 13^a the following circuit: contact 13^a, main 13, conductor 20, relay magnet 21, relay contact 21^a, attracted relay armature 21^b, conductor 22, lamp 8, conductor 12^a, main 12, conductor 17^a, source 17, conductor 19, and relay armature 18^a. Incidentally, with this circuit open at 13^a, the power of relay magnet 21 ceases, and relay armature 21^b is drawn away by its spring 21^c from the relay contact 21^a, breaking one terminal connection that was in effect between two forwardly-extending conductors 23 and 24 whose fore ends form a jack 25 having a spring cam 25^a. The continued advance of the button E first trips the blade 15, which breaks the first-traced circuit, permitting the relay armature 18^a to be drawn back by its spring 18^b to the contact 13^a as shown; and then, the button crowds the spring cam 25^a to close the jack 25. This action forms a circuit as follows: conductor 23, relay armature 21^b, conductor 22, lamp 8 (for indicator E') conductor 12^a, main 12, conductor 17^a, source 17, conductor 19, relay armature 18^a, main contact 13^a, main 13, conductor 20, relay magnet 21 and relay contact 21 with which relay armature 21^b is now in contact by attraction. Thus only the lamp 8 for indicator E' is now in operation; yet, the immediate release of the button to occasion its self-return will not cause the circuit of this lamp to be broken, as the magnetic contact at 21 and 21^b will continue without the conductors 23 and 24 in the circuit. The self-return of the button E occasions no other contact, as the insulation flange 11 alone trips the blade 15.

Reading the above operations into the con-

trol of the table legends, it will be seen that, for example, the pushing of the button D will first cause the extinguishing of any lamp 8 then in operation (except for indicator T'), and that the further advance of the button will light the lamp of indicator D'. The suit energizing button should be operated at the same time with the arrow energizing button; at least, the latter should not be allowed to recede before the suit energizing button has been fully advanced, in order that one button may not extinguish the lamp lighted by the other.

Only the circuit for the button E has been shown in full and the lamp control connections enclosed as a unit in the dotted rectangle X. For the other lamps controllable by the player the unit X is represented by the smaller rectangles Z without detail. For the other players similar connections to the corresponding buttons and lamps by extending the mains 13 and 14 to each zone of control.

The time button T is preferably insulated at 26 from the panel 5^a and makes a simple jack contact 27 for the T' lamp by way of conductors 28, 19, source 17, conductor 17^a, main 12, conductor 12^a, lamp 8 and conductor 29. Obviously, the time buttons for the other players are similarly wired to control the same lamps.

I claim no novelty for the above-described wiring system since it may be varied by the skill of one engineer or another to bring about the same ultimate result. At the same time, it may easily be conceived that the entire network may be very compactly housed in a comparatively shallow table-top, so as to render the latter light and easy to handle. Further, with the arrangement properly designed, the parts thereof may be so engineered as to involve a simple construction and an economical cost of production. The current for the electrical make up of the table may be secured by leading a cord to a convenient service outlet in a wall or floor.

While I have illustrated and described my invention in the preferred embodiment, it will be evident that the same is capable of many minor changes and refinements, and I desire to claim such changes and refinements as coming within the spirit and scope of the appended claims.

I claim:

1. A card table having spaced top and bottom surfaces, a plurality of lamp boxes disposed between said top and bottom, lamps in said boxes, transparent indicia bearing windows for said boxes extending flush with the top of said table and indicating the four suits of a card deck and the four sides of the card table, and means at each side of said table for illuminating certain lamps in said lamp boxes.

2. A card table having spaced top and bottom surfaces, a plurality of lamp boxes

disposed between said top and bottom, lamps in said boxes, transparent indicia bearing windows for said boxes extending flush with the top of said table and indicating the four 5 suits of a card deck and the four players at the sides of the table, means for illuminating any desired lamp in the lamp boxes having the indicia for the four suits from any side of the table, and means at each side of 10 the table for illuminating the next adjacent position to the left to indicate the next dealer.

In testimony whereof I affix my signature,
AUGUST KAUFMANN.
